UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

1,419,698.

Specification of Letters Patent. Patented June 13, 1922.

Application filed April 22, 1920. Serial No. 375,676.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to means for facilitating the proper relative positioning of 10 work-sheets on a platen, and is herein disclosed as applied to the Underwood standard typewriting machine.

In the class of work to be handled by 15 machines to which this invention is applied, names and addresses or the like are to be written on a record-sheet and carbon copies made on bills or forms, which are fed into the machine in strips, each of which comprises a plurality of said bills or forms. If 20 desired, carbon copies of the names and addresses may also be made on a tally-strip. Inasmuch as the printing of the names and addresses on the record-sheet is to check up 25 the writing of the names and addresses on bills or forms to be filled out later, it is desirable to have successive names and addresses written close together on the record-sheet, while the names and addresses on the 30 strip of bills are comparatively far apart.

In carrying out this invention, the strip of forms is delivered from the platen to a paper-table which may be adjustable in width, and also adjustable as a whole parallel to the axis of the platen. Provision may 35 be made of a leading-edge-gage on the paper-table. The record-sheet may be supported above the paper-table by suitable means such as arms parallel to the axis of 40 the platen, the forward edges of said arms being in alignment and serving as a means for properly gaging the leading edge of the record-sheet when the latter is introduced into the machine.

45 In order to facilitate the positioning or collating of the record-sheet and the form-strip, so that a form subsequent to the first may be properly positioned relatively to the record-sheet, provision is made of a suitable 50 bail, swingable to and from effective position, and of means tending to hold said bail in either its effective position or in an ineffective position. The bail may be provided with suitable means, such as rolls, to press 55 the record-sheet against the aforesaid arms

when the bail is swung to effective position. An arm secured to the bail is provided with a device to co-operate with the form-strip, to assist in positioning the successive forms. The last-mentioned device preferably comprises a spring-pressed pin or penetrating member, adapted to enter a perforation in the form-strip when the perforation is brought into register with an aperture in the paper-table. Obviously, a plurality of 65 spring-pressed pins may be used, the forms or bills and the paper-table being modified to co-operate therewith.

It should be understood that before the introduction of the record-sheet and the 70 form-strip, with a suitable carbon-sheet therebetween, the usual feed-rolls are cast off in the usual manner. The leading edge of the record-sheet is then brought into coincidence with the forward edges of the supporting arms, and the leading edge of the 75 form-strip is brought into engagement with the leading-edge-gage on the paper-table. When desired, the bail may be thrown into effective position after the record-sheet has 80 been properly gaged, in order to hold the record-sheet in position while the form-strip is being brought into engagement with the leading-edge-gage on the paper-table. The feed-rolls may then be restored to normal 85 90 position, to enable feeding of the record-sheet and the form-strip with the platen, and the bail thrown to ineffective position so as not to interfere with the feeding of the record-sheet and form-strip.

After writing the name and address on two or more lines, the platen may be line-spaced to advance the record-sheet into position of the first line of the new name and address. The bail may then be thrown to 95 effective position, to press the record-sheet against the supporting fingers and to bring the spring-pressed pin into engagement with the form-strip. The usual feed-rolls may then be released from the platen, and the 100 form-strip drawn forward until the spring-pressed pin drops into a perforation brought into register with an aperture in the paper-table, thus automatically arresting the form-strip or sheet. A new form 105 or bill will then be properly positioned for receiving the first line of the name and address thereon. The feed-rolls may then be restored to effective position relative to the platen, and the bail withdrawn to ineffective 110

tive position, so that line-spacing will not be interfered with.

Other features and advantages will hereinafter appear.

5 In the accompanying drawings,

Figure 1 is a perspective view of the platen frame of an Underwood standard typewriting machine, with my invention applied thereto.

10 Figure 2 is a front view of the structure shown in Figure 1.

Figure 3 is a sectional side view, showing work-sheets in adjusted position for typewriting the name and address on the first bill 15 or form of the work-strip, the bail being shown in the position in which it is placed to hold the record-sheet in position.

Figure 4 is a sectional side view similar to Figure 3, but showing the spring-pressed 20 pin prevented from entering the corresponding perforation in the paper-table by means of the strip of forms.

Figure 5 is a sectional side view, showing the record-sheet and the form-strip in position for the second name and address to be written thereon, the bail and spring-pressed pin being shown in dot-and-dash 25 lines in the position assumed when typewriting and line-spacing are to be effected.

30 Figure 6 shows the strip or detachable forms in connection with the paper-table to receive the same.

Figure 7 shows the record-sheet in connection with the arms for supporting the 35 same and the feed-rolls for holding the record-sheet on the supporting arms.

Figure 8 shows a modified form of the strip of detachable forms in which the perforations between successive bills are 40 made larger for use in connection with gagging the form-strip in order to dispense with separate perforations.

Figure 9 is a view similar to Figure 5, but shows a modified form of the device for 45 engaging the form-strip adapted to co-operate with the grip shown in Figure 8.

Figure 10 is a detail view of the device shown in Figure 9.

Figure 11 is a diagrammatic view to illustrate the condition in which one or more of the independently-movable spring-pressed pins may register with and enter perforations between forms although others do not.

The revoluble platen 1 is supported, by 55 means of an axle 2, in end-frames 3 of the platen-frame 4 of the usual Underwood typewriting machine, and the platen may be fed by means of a finger-wheel 5 on the axle, or by means of a line-space lever 6, acting through a slide 7 and a pawl 8, to drive a line-space ratchet-wheel 9 fixed on said axle 2. The extent of such actuation of the line-space ratchet may be determined by the position of a regulator 10.

65 The line-spacing mechanism just described

is, in general, similar to that disclosed in the patent to Frederick A. Hart, No. 1,281,160, dated October 8, 1918.

In order that the work may be fed forward by the platen when the latter is actuated either by the finger-wheel 5 or the line-space lever 6, provision may be made of front feed-rolls 11 and rear feed-rolls 12, supported by levers 13 and 14, respectively, said levers being pivotally mounted 70 on a shaft 15 and normally urged by suitable springs (not shown) to press the feed-rolls against the platen. When it is desired to release the feed-rolls 11 and 12 for any reason, a feed-roll-release lever 16 75 may be operated to move a link 17 and an arm 18 on a shaft 19 to turn said shaft 19 and thereby move levers 13 and 14 to withdraw feed-rolls 11 and 12 from the platen. It will be seen that such movement of levers 80 13 and 14 is effected by suitably-shaped portions of shaft 15, extending between the downwardly-extending arms of levers 13 and 14. The feed-roll-releasing means just described is substantially the same as that 85 disclosed in said patent to Hart, No. 1,281,160.

90 The bill-strip 20 (Figure 6), when inserted in the machine, may be received by a paper-table 21 adjacent the delivery side of

95 the platen, said paper-table 21 comprising sections 22 and 23 having edge-guides 24 and 25, respectively. Said sections 22 and 23 may

100 be adjustable with respect to each other to vary the width of the paper-table, and secured in such adjusted relation by any suitable means, such as indicated at 26. The sections 22 and 23 may also be provided with

105 slots 27, through which pass screws 28, threaded into a support 29, which, in turn, is connected at its ends to plates 30 supported by rods 31. Said rods 31 may be supported in any desired manner on the platen-frame.

Said section 22 of the paper-table may be provided with a leading-edge-gage 32, preferably formed by being struck upwardly 110 from said section 22.

In order to support the record-sheet 33 so that it will be spaced from said paper-table 21, brackets 34 and 35 are attached to support 29 at the left and right, respectively, of the paper-table 21, and are provided with arms 36 and 37 parallel to the paper-table 115 and spaced therefrom. These arms serve to support and guide the record-sheet as it is delivered from the platen. It will be noted

120 that the arm 36 of the left-hand bracket extends to the right, and that the arm 37 of the right-hand bracket also extends to the

125 right and is provided with a side-edge-gage 38. It should be understood that the record-sheet and form-strip are guided to the platen by means of a rear paper-table 4^a of the usual form in the Underwood typewriting

130

135

The arrangement just described enables the use of a record-sheet wider than the form-strip, and also enables the positioning of the left-hand edge of the record-sheet to the right of the corresponding edge of the form-strip, for a purpose to be brought out hereinafter. The advance edges of arms 36 and 37 are in alignment, and may be used in properly positioning the record-sheet when 5 first introduced into the machine.

When it is desired to insert a record-sheet and a form-strip, with a carbon-sheet interleaved therebetween, into the machine, the feed-rolls 11 and 12 are released, the record-sheet is positioned by means of the aligned 15 edges of arms 36 and 37, and the leading edge of the form-strip is brought into engagement with the leading-edge-guide 32. The feed-rolls 11 and 12 may then be restored to effective position. Such positioning of the record-sheet and the form-strip may be facilitated by providing means for holding the record-sheet in position on arms 36 and 37 while the form-strip is being 20 brought to proper position. Such holding of the record-sheet may be obtained by means of feed-rolls 39, mounted on a rod forming part of a bail 40, which is supported, by means of arms 41 forming part thereof, on shafts 42. Said shafts 42 may be journaled in plates 43, secured to the respective end-frames 3 in any desired manner. In order to maintain the bail in effective position with the rolls 39 in contact with arms 36 25 and 37, or in a position withdrawn therefrom, shafts 42 may be provided with heads 44, having recesses 45 properly shaped to receive circular disks 46, carried by arms 47, pivoted at 48 and urged by springs 49 to force said disks 46 into the recesses 45. Said feed-rolls 39 may be shiftable along the rod 30 on which they are mounted, so as to engage arms 36 or 37 where desired.

To properly determine the position of the bills following that first written, each bill is perforated at 50, so that, when the perforation in a given bill is brought into register with a perforation 51 provided in section 22 of paper-table 21, a pin 52 may be inserted into the perforation in the bill to position the same for writing the first line of the name and address thereon. As indicated in Figure 1, the left-hand edge of the record-sheet is positioned to the right of the corresponding edge of the bill-strip so as to avoid interference, by the record-sheet, with said pin 52. Said pin 52 may be supported in a sleeve 53 on an arm 54, attached by means of screws 55 to the arm 41 at the left, as seen in Figure 1, and may be pressed toward the paper-table by means of a light spring 56, movement of the pin by the spring being limited by means of a nut 57 at the upper end of a stem 58 forming part of said 65 pin.

After the record-sheet and form-strip or bill-strip have been placed in the machine, as shown in Figure 3, the bail 40 may be swung forward to the position indicated in Figure 5, and typewriting effected by means of type-bars 59, striking through a ribbon 60, to print on the record-sheet 33; a copy of such typewriting being obtained on the bill-strip by means of a suitable carbon-sheet 61. When desired, a tally-strip 62 and carbon- 70 sheet 63 may also be used. The feeding of the tally-strip may be effected by suitable means, such as disclosed in said patent to Hart, No. 1,281,160.

After writing each line of the name and address on the first bill, the platen is actuated by the line-space lever, the last actuation thereby serving to advance the record-sheet to a position for writing the first line of the second name and address thereon. The bill-strip will not, however, be properly positioned to receive the carbon-copy of the second name and address. In order to effect such positioning of the bill-strip, the bail 80 may be swung to the rear, so that rolls 39 85 will press record-sheet 33 against arms 36 and 37, and will bring pin 52 into yielding engagement with bill-strip 20, as indicated in Figure 4. Feed-rolls 11 and 12 may then be released, and bill-strip 20 drawn forward 90 until the next aperture of perforation 50 in the bill-strip is brought into register with the aperture 51, whereupon pin 52 will assume the full-line position shown in Figure 5. The feed-rolls 11 and 12 may then be restored to effective position, and the bail 100 swung away from the paper-table, as indicated in Figure 5. Obviously, the shifting of the bill-strip will be effected in the same manner for any subsequent bill.

Instead of using separate perforations 50 in the bill-strip, as indicated in Figure 6, the perforations between the detachable forms or bills may be utilized. In this case, the individual perforations may be made 110 somewhat larger, as indicated in Figure 8, and the single spring-pressed pin may be replaced by a device such as shown in Figures 9 and 10. With this arrangement, when the bill-strip is advanced to bring the line 115 of perforations 64 into proper position, certain perforations may be engaged by a plurality of pins 65, mounted upon a modified form of arm 54, and lightly pressed to effective position by spring-fingers 66, which 120 may be formed as part of a single plate 67, secured on the supporting arm. As indicated in Figure 11, one or more of the independently-movable pins may register with and enter perforations between forms or bills 125 although others do not. It is apparent therefore, that accurate positioning of the perforations in the lines of division is not so important as in the case where each form is provided with a single perforation to co- 130

operate with a single pin. In connection with the use of the plurality of pins 65, an elongated opening 68 may be provided in the paper-table, or provision may be made of 5 one opening for each pin. Obviously, the device shown in Figures 9 and 10 may be used in connection with a bill-strip having a line of perforations different from and in addition to those between the separate bills.

10 As shown in Figure 7, the record-sheet may have perforations 69 to facilitate the filing of the same.

Variations may be resorted to within the scope of the invention, and portions of the 15 improvements may be used without others.

Having thus described my invention, I claim:

1. In a typewriting machine, in combination, a revoluble platen, means to grip a 20 work-sheet at the delivery side of the platen, a spring-pressed pin to co-operate with perforations in a second work-sheet, to determine the proper positioning of the same at different times, and means to concomitantly 25 render said gripping means effective and cause said spring-pressed pin to yieldingly engage said second work-sheet, so that the latter may be drawn forward with reference to the first work-sheet until said pin enters 30 one of said perforations in the second sheet and prevents further movement thereof.

2. In a typewriting machine, in combination, a revoluble platen, normally ineffective means to engage a work-sheet at the delivery 35 side of the platen and prevent advance thereof, a device, normally in ineffective position, for co-operating with a second work-sheet at certain points therealong determined by the configuration of said second sheet, and 40 preventing advance movement thereof, and means for concomitantly rendering said engaging means effective to prevent advance movement of the first-mentioned work-sheet and to move said device to operative position, 45 so that said second work-sheet, after being advanced to one of said points where said device may co-operate therewith, will be held against further movement.

3. In a typewriting machine, in combination, a revoluble platen, a platen frame, a 50 front paper-table, aligned arms spaced from said paper-table, a swingable frame pivoted on said platen frame, engaging devices on said swinging frame adapted to hold a work- 55 sheet against said arms, and means carried by said frame to co-operate with a second work-sheet of a suitable configuration on said paper-table to facilitate the proper positioning of the second work-sheet with respect to the first.

4. In a typewriting machine, in combination, a revoluble platen, a platen frame, a front paper-table, a front edge gage on said 60 paper-table, aligned arms spaced from said

paper-table, a swingable frame pivoted on 65 said platen frame, engaging devices on said swingable frame adapted to hold a work-sheet against said arms, and means carried by said frame to co-operate with a second work-sheet of a suitable configuration on 70 said paper-table to facilitate the proper positioning of the second work-sheet with respect to the first.

5. In a typewriting machine, in combination, a revoluble platen, means to guide 75 therearound a record sheet and a strip comprising a series of detachable sheets of equal lengths, normally ineffective means to hold said record sheet against movement, and normally ineffective means effective when 80 said holding means is made effective to co-operate with said strip when the latter is drawn forward, and thereby properly position one of said detachable sheets for the first writing line thereon.

6. In a typewriting machine, in combination, a revoluble platen, means to feed 85 therearound a strip of detachable forms, said strip having transverse lines of perforations between said forms, and a gaging 90 device comprising spring-pressed penetrating members adapted to enter the perforations between said forms as the strip is drawn forward and thereby position said strip.

7. In a typewriting machine, in combination, a revoluble platen, means to guide 95 therearound a strip comprising portions of equal length having lines of perforations therebetween, and means adapted to co-operate with the perforations in any one of 100 said lines, and properly position one of said portions of the strip for the first writing line thereon.

8. In a typewriting machine, the combination with a revoluble platen, of a paper-table to receive a work-strip from the platen, supports to receive a record sheet carried around said platen with said work-strip, feed-rolls to hold said record sheet 110 against said supports, a spring-pressed pin to co-operate with perforations in said work-strip to position the same, and a movable frame whereby said feed-rolls and said spring-pressed pin may be moved to and 115 from operative position.

9. In a typewriting machine, the combination with a revoluble platen, of a front paper-table, a ridge thereon adapted to act as a leading-edge gage, arms to support a work-sheet in front of said table, a frame movable toward and away from said paper-table, holding members to co-operate with said arms mounted on said frame, and a 120 spring-pressed penetrating device mounted on said frame and adapted to engage perforations in a second work-sheet to properly position the same, said paper-table being 125

- perforated to permit penetration thereof by the penetrating device except when obstructed by the second work-sheet.
10. In a typewriting machine, in combination, a revoluble platen, a platen frame, a paper-table at the delivery side of the platen to receive a work-sheet fed therefrom, a support on which said paper-table is adjustable longitudinally of the platen, brackets mounted on said support, each of said brackets comprising an arm spaced from said paper-table, said arms constituting supporting means for an outer work-sheet, and a side edge gage on one of said arms.
- 15 11. In a typewriting machine, in combination, a revoluble platen, a platen frame, a paper-table at the delivery side of the platen to receive a work-sheet fed therefrom, said paper-table comprising two sections adjustable to vary the width thereof, a side edge gage on each of said sections, a support on which said paper-table is adjustable longitudinally of the platen, brackets mounted on said support, each of said brackets comprising an arm spaced from said paper-table, said arms constituting supporting means for an outer work-sheet, and a side edge gage on one of said arms.
- 20 12. In a typewriting machine, in combination, a revoluble platen, a paper-table to receive from said platen a work-sheet comprising a series of forms, means to support a second work-sheet outside of the first and spaced from said paper-table, said paper-table and said supporting means having provisions whereby the leading edges of the respective sheets may be properly positioned with respect to each other, and means made effective at will to co-operate 25 with said supporting means to hold the outer sheet against movement, and to co-operate with the inner sheet to permit the same to be drawn forward until the next form is properly positioned with reference 30 to the printing point, and then to prevent further movement of that sheet.
13. In a typewriting machine, in combination, a revoluble platen, means to feed therearound a strip of detachable forms, a record sheet outside of said strip, a support for said strip positioned to receive the same from the delivery side of the platen, supporting means for maintaining the record sheet in spaced relation with respect to the 35 strip support, a swingable frame, devices on said frame to co-operate when said frame is in effective position with said supporting means to hold the record sheet, and a pin on said frame yieldingly urged when said 40 frame is in effective position to enter an opening in said support, but prevented from entering the same in case an imperforate portion of the work-strip prevents such entrance, whereby the work strip may 45 be properly positioned by drawing the same
- forward until a perforation therein is brought into position to receive said pin.
14. In a typewriting machine, in combination, a platen, means to co-operate therewith to feed therearound a strip of detachable forms provided with perforations, a record sheet outside of said strip, means including a spring-pressed feeler to concomitantly grasp said record sheet to hold the same and to bring said feeler against said strip, so that when the latter is drawn forward until the feeler enters a perforation therein another form on said strip will be in position to be printed upon.
15. In a typewriting machine, in combination, a platen, line-spacing means therefor, means for maintaining in operative relation with said platen, to be fed thereby, a record sheet and a strip comprising a plurality of forms arranged in succession, means whereby said maintaining means may be made ineffective when one or more lines have been printed on said record sheet and strip and the platen line-spaced to advance the record sheet, and gaging means for gripping said record sheet to hold the same against movement, and for co-operating with said strip, when the same is drawn forward, to check the movement thereof when the next form is brought into proper position with reference to the record sheet.
16. In a typewriting machine, in combination, a revoluble platen, feed-rolls to co-operate therewith for feeding work-sheets, means to release said work-sheets from said platen and said feed-rolls, means to hold one of said work-sheets when the releasing means has been operated and while another of said work-sheets, having openings at predetermined intervals, is being shifted longitudinally, and positioning means for said last-mentioned work-sheet including a yieldably-urged pin to enter one of said openings, brought into register therewith, and prevent further longitudinal movement.
17. In a typewriting machine, in combination, a platen, a frame therefor, a bar above said platen and extending longitudinally thereof, a paper-table to receive a work-sheet from the platen, said paper-table comprising two parts, each of which has an edge gage thereon, said parts being adjustable with respect to each other to receive work-sheets of various widths, means whereby said paper-table may be adjustably secured to said bar at different positions along said platen, a leading-edge gage on one of said parts, brackets to secure said bar at each side of said paper-table and extending beyond the level of said table, one of said brackets having an arm extending over said paper-table, the other of said brackets having an arm extending away from said paper-table in substantially the same plane as the first-mentioned arm, so that the two

arms may form a support for a sheet outside of the one resting on the paper-table, and wider than the inner sheet, and a side edge gage on said second-mentioned arm.

5 18. In a typewriting machine, in combination, a revoluble platen, a paper-table to receive a work-sheet from said platen, means for supporting a second work-sheet above said paper-table, a swinging bail movable 10 to effective and ineffective positions, devices on said bail for clamping the first sheet against said supporting means when said bail is in effective position, an arm on said bail, and a spring-pressed pin on said arm 15 to enter a perforation in the paper-table when said bail is in effective position.

19. In a typewriting machine, in combination, a revoluble platen, feed-rolls to co-operate therewith for feeding work-sheets, 20 means to release said work-sheets from said platen and said feed-rolls, means to hold one of said work-sheets when the releasing means has been operated and while another of said work-sheets, having openings at pre- 25 determined intervals, is being shifted longitudinally, positioning means for said last-mentioned work-sheet including a spring-pressed pin to enter one of said openings, brought into register therewith, and pre- 30 vent further longitudinal movement, and means to render said pin and said holding means effective and ineffective concomitantly.

20. In a typewriting machine, in combination, a revoluble platen, feed-rolls to co- 35 operate therewith, releasing means to separate said platen and feed-rolls, normally ineffective means to engage a work-sheet at the delivery side of the platen and prevent longitudinal movement thereof, a normally 40 ineffective device for co-operating with a second work-sheet at certain points there- along determined by the configuration of said second sheet and preventing longitudinal shifting thereof, and means for render- 45 ing said normally ineffective preventing means and said device effective to enable a proper relative positioning of the work- sheets to be effected when said releasing means has been actuated.

50 21. In a typewriting machine, in combination, a revoluble platen, guiding means for a work-sheet, holding means to co-operate with said guiding means to prevent longitudinal movement of the work-sheet, sep- 55 arate guiding means for a second work-sheet having a predetermined configuration, gag- ing means to co-operate with the second work-sheet to position it in accordance with said predetermined configuration, and means 60 to render said holding means and said gag- ing means effective or ineffective at will.

22. In a typewriting machine, in combination, a platen and collating means for effect- 65 ing a proper relative longitudinal adjust- ment of superposed work-sheets on the

platen, said collating means including means for holding one of said work-sheets against longitudinal movement, and arresting means for another work-sheet having perforations at predetermined intervals, the effectiveness 70 of said arresting means being controlled by the perforated sheet, whereby, upon reaching any one of the positions indicated by the perforations, the perforated work-sheet will be arrested.

75 23. In a typewriting machine, the combination with a platen, of means for collating superposed work-sheets, comprising a pin yieldably urged into engagement with one of said work-sheets to enter an opening 80 therein to determine the proper position of the work-sheet when the latter is drawn along until said opening is positioned to receive the pin, and means to hold another work-sheet against movement while the 85 work-sheet having the opening therein is being shifted.

24. In a typewriting machine, the combination with a platen, of means for collating superposed work-sheets, comprising a 90 pin yieldably urged into engagement with one of said work-sheets to enter an opening therein to determine the proper position of the work-sheet when the latter is drawn along until said opening is positioned to receive the pin, means to hold another work- sheet against movement while the work-sheet having the opening therein is being shifted, and means whereby said pin and said holding means may be made ineffective con- 95 mitantly.

100 25. In a typewriting machine, the combination with a platen, of collating means comprising a spring-pressed pin for yieldably engaging a work-sheet to enter a perforation therein when the latter is brought beneath said pin, so as to prevent further movement of the work-sheet, manually-operable means to withdraw the pin from the perforation in the work-sheet, and means to 105 hold another work-sheet against movement while the first-mentioned work-sheet is being shifted.

110 26. In a typewriting machine, the combination with a revoluble platen, of feed- 115 rolls co-operative therewith to hold work- sheets thereagainst, means for separating the feed-rolls and the platen, means for positioning a work-sheet, comprising a pin yieldingly pressed toward the work-sheet, so as to 120 enter an opening therein, when the work- sheet is advanced to the proper position, and prevent further movement, and means for holding a second work-sheet during the for- 125 ward movement of the first-mentioned work- sheet.

130 27. In a typewriting machine, the combination with a revoluble platen, of feed- rolls, co-operative therewith to hold work- sheets thereagainst, means for separating the

feed-rolls and the platen, means for positioning a work-sheet, comprising a pin yieldingly pressed toward the work-sheet, so as to enter an opening therein, when the work-sheet is shifted to the proper position, and prevent further movement thereof, means for holding a second work-sheet during the shifting movement of the first-mentioned work-sheet, and means to render said pin and said holding means effective and ineffective concomitantly.

28. In a typewriting machine, in combina-

tion, a platen around which superposed work-sheets and interleaved carbons are fed, and collating means made effective at will ¹⁵ whereby one of said sheets will be held against longitudinal movement and another sheet be arrested automatically after advancement to a predetermined position.
